ATTORNEY

UNITED STATES PATENT OFFICE

100,938

DESIGN FOR AN AUTOMATON MERCHANTISING DEVICE

Frank L. Dale, Hartselle, Ind.

Application June 20, 1936, Serial No. 63,408

Term of patent 14 years

To all whom it may concern:

Be it known that I, Frank L. Dale, a citizen of the United States, residing at Hartselle, county of Bartholomew, State of Indiana, have invented a new, original, and ornamental Design for an Automaton Merchandising Device, of which the following is a specification, reference being had to the accompanying drawing, forming part thereof.

In the drawing:

Fig. 1 is a front elevation of an automaton merchandising device showing my new design, and

Fig. 2 is a side elevation thereof.

I claim:

The ornamental design for an automaton merchandising device as shown.

FRANK L. DALE.
